UNITED STATES PATENT OFFICE.

WILLIAM McELROY, OF BROOKLYN, NEW YORK, ASSIGNOR OF ONE-HALF TO MICHAEL LUDGIN, OF BROOKLYN, NEW YORK.

SPARK PLUG.

Application filed May 29, 1926. Serial No. 112,467.

This invention is a spark plug. The object of the invention is to provide a plug of relatively simple construction, but capable of high efficiency through long periods of use. The invention is more particularly directed to the electrodes of the plug and consists, generally speaking, in the provision of electrodes which are capable of adjustment in such manner as to present different portions of the electrodes at the point of sparking, so that when one portion of each electrode becomes pitted or badly disintegrated, another portion of such electrode may be presented at the gap.

I have discovered that the foregoing objects may be efficiently and economically obtained by making the electrodes in the form of spiral springs and so mounting the springs that they are capable of movement either in the nature of bodily movement or of distending operation to present different portions of the springs at the gap.

I am aware that it has been heretofore proposed to mount coil springs of wire upon the electrodes of a conventional plug in such manner that the inherent resiliency of the coil springs used in this connection will grip the conventional electrodes and be held in place by such frictional engagement. Experience has shown, however, that when a coil spring is subjected to the rapid continued variation in temperatures to which the electrode of a plug is subjected, springs thus associated with the electrode will not only lose their resiliency, but will appreciably expand and drop off into the motor, thereby constituting a serious hazard to the mechanism.

The present invention is not to be confused with this prior practice, since the electrodes, per se, are in the form of coils of wire and are not separate and independent coil springs associated with an electrode.

In the preferred manner of carrying out the present invention, the central electrode is in the form of a rod which extends through the porcelain with a binding post associated with the upper end of the rod and the lower end of the rod formed into a series of coils or convolutions. The grounded electrode is mounted upon a suitable guide, in the form of a yoke, both ends of which are anchored to the shell of the plug and the coil which constitutes the grounded electrode

embraces this yoke and is either mounted for free longitudinal movement on the yoke or is anchored in such manner that movement of the coil to present different portions thereof at the cap is manually obtained by stretching the coil. As thus specified, there is no possibility of the coils becoming disengaged from the plug and the desired adjustments may be made from time to time as occasion may require in a simple and expeditious manner.

Features of the invention, other than those specified, will be apparent from the herein-after detailed description and claims, when read in conjunction with the accompanying drawings.

The accompanying drawings illustrate different practical embodiments of the invention, but the constructions therein shown are to be understood as illustrative, only, and not as defining the limits of the invention.

Figure 1 is a vertical central section of a spark plug embodying the present invention.

Figure 2 is a bottom plan view of the plug shown in Figure 1.

Figure 3 is a view similar to Figure 2, but illustrating a modified form of the invention; and,

Figure 4 is a side elevation, partly in section of a modified form of central electrode.

The plug shown in the drawings embodies the usual metal shell 1 having a threaded shank 2 and interiorly of which is mounted a porcelain 3 held rigidly in position by a jamb nut 4.

In the construction shown in Figures 1 to 3, the central electrode is in the form of a rod or wire 5 which extends longitudinally through the porcelain and is provided at its lower end with a series of coils or convolutions. The coil portion of the wire 5 extends into the lower end of the porcelain, which is chambered as shown at 7 to receive it.

The purpose of this construction is to permit the coil portion of the rod to be properly supported against lateral movement which might seriously vary the dimension of the gap of the plug. The upper end of the rod or wire 5 is bent over the upper portion of the porcelain as shown at 8 and a metal cap 9 is spun over the upper portion of the porcelain so as to make good electrical contact with and cover the upper end of the

rod 5. This metal cap carries a suitable binding post 10 with which is associated conventional nuts 11.

In the construction of Figure 4, the coil 5^a, which constitutes the central electrode, is made separate from that portion 5^a of the stem which extends through the porcelain, but is attached thereto by carrying the upper end of the coil through a perforation in the rod 5 and then bending the wire of the coil as shown at 12 to permanently lock the parts together. The rod 5 is shown as extending downwardly into the coil 6^a for a distance for the purpose of steadyng the coil 15 against lateral movement, but if the upper portion of the coil is housed within a pocket 7^a in the porcelain corresponding to the pocket 7 of Figure 1, the rod need not extend downwardly as shown, but may terminate just below the perforation where the end of the coil is secured to the rod. The upper end of the rod is provided with the usual nuts for securing the ignition lead to the plug.

25 The grounded electrode may be constructed as shown in either Figures 2 or 3. In Figure 2, a yoke 14, preferably of heavy wire, is secured at both of its ends to the lower end of the shank 2. About this yoke, 30 the electrode 15 is coiled. One end of the coil is left free, while the other end is anchored to the shell as shown at 16.

In Figure 3, the structure is in many respects similar to that of Figure 2, except that 35 the grounded electrode 15^a is unattached and is adapted for free sliding movement longitudinally of the yoke.

When a plug is provided with electrodes of the character described, it will be apparent that that portion of the central electrode which cooperates with the grounded electrode at the gap may be varied as desired. Initially, the central electrode is in the form of a close coil, and the lower end thereof is 40 juxtaposed with the grounded electrode. If such lower end becomes badly pitted or burned away, the coil may be slightly distended or elongated to present a new portion thereof at the gap and this operation 45 may be repeated from time to time as circumstances require to maintain a proper operating condition of the central electrode.

50 In practice, this elongation of the coil may be expeditiously accomplished, since the coil 55 does not possess any appreciable inherent resiliency and will, in fact, stay in substantially the position to which it has been adjusted. The same manner of adjustment is true with respect to the construction of Figure 2, it being manifest that the coil may be 60 shifted manually longitudinally of the yoke to present different operative portions of its length at the gap. In Figure 3, however,

the vibration of the car will serve to constantly vary the position of the coil on the 65 yoke, so as to bring about an automatic constant change at the gap.

By employing coils in the manner in which I have described, the vibration of the engine will cause an almost constant movement of the coils. This movement is in practice very slight, so slight in fact that it would not be perceptible to the eye. Nevertheless there is a movement of the parts which insures cleanliness of the electrodes 75 since by virtue of such movement, the deposit of extraneous matter such as carbon is rendered impossible.

It is to be understood, however, that the movement to which I have referred will not 80 seriously interfere with the maintenance of the desired gap nor will such movement preclude proper functioning of the plug. Nevertheless the parts will be kept clean and operative through long periods. The invention is of simple construction, economical to 85 manufacture and highly efficient in operation.

The drawings show the invention in its preferred practical forms, but the invention 90 is to be understood as fully commensurate with the appended claims.

Having thus fully described the invention, what I claim as new and desire to secure by Letters Patent is:

1. A spark plug embodying a shell, a grounded electrode at the bottom of said shell, a porcelain provided in its lower end with a pocket and mounted on the shell, a central electrode extending through the porcelain and with an integral formed coil of wire extending from within the pocket to a point adjacent to and laterally of the grounded electrode and forming therewith the gap of the plug, said coil being of 100 easily bendable wire, initially formed with closely spaced convolutions adapted to be manually elongated from time to time to present different convolutions of the coil at the gap. 105

2. A spark plug embodying a shell, a porcelain associated therewith, an insulated electrode extending through the porcelain, a substantially U shaped yoke, both arms of which are anchored in the shell and the intermediate part of which is longitudinally curved to extend around the side of the insulated electrode, and a grounded electrode in the form of a coil loosely embracing the laterally curved part of said yoke and mounted to freely shift longitudinally thereof. 115

In testimony whereof, WILLIAM McELROY has signed his name to this specification this 28th day of May, 1926.

WILLIAM McELROY.
